UNITED STATES PATENT OFFICE

WILLIAM H. SCHULTE, OF TRENTON, NEW JERSEY

FLUSH TANK

Application filed February 24, 1928. Serial No. 256,728.

This invention relates to improvements in operating mechanism for flush tanks and the like, and especially to mechanism in which the flush valve is held open by a float for slow 5 closure thereof and refill.

Among the objects of the invention are the removal of the resistance of the float from the valve and the prevention of the rising of the float affecting the valve as the tank fills. 10 A further object of the invention is to provide operating mechanism which is adaptable for use with bowls of various sizes.

In the accompanying drawings forming a part of this specification, there is shown for 15 the purpose of illustration, a flush tank of the preferred form embodying all the features of the invention, and this flush tank will now be described in detail and the features forming the invention then specifically 20 pointed out in the claims.

In the drawings:

Figure 1 is a vertical section through the flush tank partly broken away, showing the operating mechanism in side elevation; 25 Figure 2 is a section on lines 2—2 of Figure 1 with parts broken away and

Figure 3 is a detail in side elevation and enlarged.

Referring to the drawing, 10 is a flush tank 30 provided with a port 11, to admit the discharge connection 12 provided with a discharge valve seat 13. The weighted discharge valve 14, in the present illustration, carries the overflow pipe 15 and these parts 35 are guided by a guide plate 16 supported by rods 17, which pass through lugs 18 carried by the valve 14 for guiding the valve itself.

The operating handle 19 and its spindle 40 20 may be connected to the valve 14 and overflow pipe 15 in any suitable manner, but preferably an adjustable sliding connection is provided which allows wide adjustment of the connection to adapt it for tanks of various 45 sizes and may well be of the form shown, in which the guide plate 16 is provided with lugs 21 adapted to receive the inturned ends of a bail 22 which cooperates with a collar 23 secured to the overflow pipe 15 by a screw 50 24. A sliding link 25 is secured by screw

26 to one of the arms of the bail 22 and is connected to the operating spindle 20 by a connecting rod 27 pivotally secured to the sliding link 25 and to a cam member 28 secured on the operating spindle 20 55 in any suitable manner as by set screw 29. Sliding connection between the cam member and its connection to the valve is desirable because the length of the connection to be made will vary with different bowls. With the sliding connection described, quite a wide variation is permissible.

It will readily be appreciated that by turning operating handle 19 in either direction the flush valve 14 will be raised from its seat 60 through the cooperation of collar 23, bail 22, link 25, connecting rod 27 and the cam 28.

It is customary to provide a float device which operates to hold the valve open and secure a slow closure of same for refill. According to the present invention, a bracket 1 carries a second cam 2 which is pivoted therein on cotter pin 3 and is held in engagement with the edge of cam 28 by a suitable float mechanism such as float 4 connected by link 5 to an arm 6 formed integrally with cam 2. The float 4 preferably operates within a section of the main tank on a small separate float tank 7 which is provided with a small escape port 8, the size of which determines 75 the rate of closure of the valve. The cam 2 is preferably in vertical alignment with the spindle 20 and thus the pivot of cam 28, so that there is no side strain on the float lever or float and the float offers no resistance to 80 the operating mechanism. The cam 28 is preferably provided with two recessed portions 9 on its upper side.

The operation of the device is as follows: When the tank 10 is full, the upward lift 90 of float 4 holds the cam 2 in engagement with the edge of cam 28 until such time as operating handle 19 is turned to raise discharge valve 14. Upon the full opening of the valve 14, cam 28 is rotated sufficiently to 95 bring one or the other of its depressions 9 over the cam 2, which is forced therein by the rising of float 4 and the valve 14 is thereby held open. When the level of the water in the main tank 10 gets down to the top of 100

the small tank 7, the level of the water in the small tank 7 drops more slowly than in the main tank 10, which keeps the valve 14 off of its seat 13. This allows the main tank 10 to practically empty itself, and keeps the main valve 14 off of its seat 13 long enough to seal the bowl. The amount of water used for sealing can be governed by the size of outlet 8 in small tank 7. The lowering of float 4 gradually withdraws cam 2 from cam 28 so that the valve 14 closes slowly until the refill has been accomplished, when cam 2 is withdrawn sufficiently to release cam 28 for a quick and complete closure of valve 14.

15 It is understood that the invention is not limited to the specific construction and details shown, as these may be varied widely within the invention as defined by the claims.

20 What I claim is:

1. An apparatus comprising a tank, a flushing valve for allowing discharge from the tank, an operating mechanism for the valve including a handle on the exterior of the tank, a spindle for the handle extending through the wall of the tank, and a cam on the spindle and within the tank, means connecting the valve and operating mechanism whereby operation of the handle opens the valve, a float within the tank, and a member cooperating with the edge of said cam and operated by said float to maintain the cam in position corresponding to open position of the valve until the float falls to a predetermined level.

2. In a flushing apparatus, the combination with a flush valve and its operating mechanism, of a rotatable cam forming a part of the operating mechanism, a pivoted cam having a surface for engaging the surface of the first cam, the plane of movement of the second cam being transverse to the plane of rotation of the first cam, and a float connected to the second cam to maintain engagement between the cams and move the second cam to hold the first cam in position corresponding to open position of the valve until the float falls to a predetermined level.

3. In a flushing apparatus, the combination with a flush valve and its operating mechanism, of a rotatable cam forming a part of the operating mechanism, said cam having a depression on its edge, a second cam having a cam surface for engaging the edge of the first cam, the plane of movement of the second cam being transverse to the plane of rotation of the first cam, and a float connected to the second cam and adapted to move the second cam into the depression of the first cam to hold the flush valve open upon movement of the operating mechanism.

4. An apparatus comprising a tank, a flushing valve therefor, a vertical overflow pipe associated with the valve, a collar on the pipe, a pivoted bail for engaging beneath

the collar, a sliding link adjustably positioned on the bail, and operating means for the link.

5. A flushing apparatus comprising a tank, a flushing valve for allowing discharge from the tank, an operating mechanism for the valve including a handle on the exterior of the tank, a spindle for the handle extending through the wall of the tank, and a cam on the spindle and within the tank, means connecting the valve and operating mechanism whereby operation of the handle opens the valve, a pivoted cam having a surface engaging the surface of the first cam, the plane of movement of the second cam being transverse to the plane of rotation of the first cam, and a float connected to the second cam to maintain engagement between the cams and move the second cam to hold the first cam in position corresponding to open position of the valve until the float falls to a predetermined level.

6. A flushing apparatus comprising a tank, a flushing valve for allowing discharge from the tank, an operating mechanism for the valve including a handle on the exterior of the tank, a spindle for the handle extending through the side of the tank, and a cam on the spindle and within the tank, a connection between the valve and operating mechanism whereby operation of the handle opens the valve, a float within the tank, a member cooperating with the edge of said cam and operated by said float to maintain the handle in its open position until the float falls to a predetermined level in the tank, and a separate float tank for said float having a restricted escape opening near its bottom for limiting the flow from the float tank and retarding falling of the float as the liquid drains through the valve.

In testimony whereof, I have hereunto set my hand.

WILLIAM H. SCHULTE.
